UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

CIRCULAR-KNITTING MACHINE FOR FABRICS OF CHANGEABLE SIZES.

1,147,649.

Specification of Letters Patent.

Patented July 20, 1915.

Application filed January 29, 1915. Serial No. 5,157.

To all whom it may concern:

Be it known that I, ROBERT W. SCOTT, citizen of the United States, and resident of Boston, in the county of Suffolk and State of Massachusetts, have invented certain new and useful Improvements in Circular-Knitting Machines for Fabrics of Changeable Sizes, of which the following is a specification.

10 My invention relates to knitting machines having elements changeable to enable the production of fabric of any one of a number of widths.

15 Economic manufacture of knit fabrics in bulk for underwear and other uses has heretofore required circular knitting machines each producing a seamless tube of fabric of one fixed size which can be utilized in an unbroken state for a great part of certain 20 garments, the manufacturer being compelled to provide for knitting as many different sizes of such tubes as there are different customary sizes of garment demanded by the trade, which results in practise in his having 25 on hand at least as many different machines. A great number of costly machines may thus stand idle when there is no demand for the size of the tube made by them.

30 One object of my invention is to avoid the necessity for the provision of machines in so many different sizes.

Another object of my invention is to provide a base machine capable of coöperation with a needle carrier or needle carriers of 35 two or more different sizes, whereby a change in the size of the product may be made by the replacement of the needle carriers only.

40 Other objects of my invention are to enable rapid and convenient conversion of a knitting machine from one size to a knitting machine of another size, and to enable the common use of the devices for supporting, driving, adjusting and performing 45 other usual functions of such machines in coöperation with needle carriers for plain knitting and needle carriers for rib knitting.

45 In the accompanying drawings: Figure 1 is a vertical section illustrating one form of my device; Fig. 2 is a fragmentary plan showing the needle cam actuator ring or carrier and a part of the bed-plate, the needle cylinder being removed; Fig. 3 is a 55 plan of a dial cam cap adapted to co-

operate with the remaining devices; Fig. 4 is an elevation of a cylinder cam segment.

The generic features of my invention are illustrated herein by one species of machine comprising a bed-plate 1 having an annular bearing groove 2 therein for a rotary cam carrier 3, which in turn is provided with the usual crown bevel teeth 4 to be driven by the customary bevel gear 5 and belt pulleys. The driving devices preferably comprise change speed gearing G of any ordinary or usual type, whereby a standard driving speed at the belt pulleys may be varied for purposes mentioned below.

50 The upper surface of the bed-plate 1 is provided with a series of annular seats 6, concentric with groove 2, and preferably having one cylindrical face, each adapted to receive the bottom edge, shaped to fit said seats, of a grooved needle carrier such as 7, of which there may be a different one for each of the different seats 6.

55 The needle cylinders 7 may be of any usual or known construction, and said cylinders are preferably held seated by screws 80 10 passing through bore holes 9 formed at suitable points in each of the annular seats 6, and through the bed-plate 1.

60 In order to actuate the needles in needle cylinder 7, actuating cams are carried by the driven carrier ring 3, said cams coöperating with needle butts projecting a short distance beyond the surface of the needle carrier 7. In order to coöperate with needle cylinders 7 of different diameters, changeable cam carrier means are provided for holding the cams to travel in or near any one of a number of different circular paths, to contact with the needle butts when in corresponding positions determined by cylinders of different diameter fitting in the 65 seats 6. The preferred construction shown in the drawings comprises a series of carrier bars 11 seated in substantially radial seats 12 formed in lugs 13 on ring 3, said bars 11 having central slots 14 through which locking screws 16 tapped into ring 3 pass. For variation of the number of knitting points or waves, machines of the type shown being customarily operated as multiple feed 70 machines, I provide a sufficient number of seats 12 for the variable positioning devices for the cams to accommodate the maximum number of yarn feeds ever to be used. For 75 one instance only, seats 12 are shown in 110

Fig. 2 spaced to provide for twenty-four evenly spaced bars 11 about the circle, thus providing for the even spacing of knitting waves and yarn feed points at any number 5 of spaces about said circle evenly divisible into 24, such as four, six, eight or twelve; and for other numbers of waves formed by assembling bars 11 in groups in adjacent slots 12.

10 Slide or bar 11 may be a cast bar having a head 15 having a plane vertical inner face, and upper and lower surfaces at suitable angles to the axis of the machine corresponding to the desired form of wave in the 15 needles, upon which cams 22, 23, 24, 25 are fastened. Said cams 22, 23, 24 and 25, which may be varied for the particular form desired to be given to the knitting wave by variations of the form of the head 15 of the 20 slide 12, are adjustably attached to head 15, as by screws 26 in slots 27 of the cams. The length of the cams 23, 24 and 25 is sufficient to enable those at the extremity of said head to be adjusted farther inward 25 than those in the center thereof to correspond to the face of the smallest cylinder in use.

The advantages of my structure so far as it is described will immediately be apparent. Instead of providing an actuator ring 3, having thereon turned cylindrical segments for one size needle cylinder only, I am enabled with minimum effort and skill to mount the needle cylinder of the desired 35 size on bed plate 1 and then individually to adjust the slides 11 to an operative position with respect to said cylinder.

A take-up mechanism shown generally at T, which may be of any approved form, a 40 base or table A, and standards a, for supporting the bed plate 1, the driving and speed reducing gear, the bed plate 1 itself, and the rings 3 may for a large variety of sizes of product be of standard form and 45 dimensions. Other parts now made of variable size may be standardized by the adaptability of the described parts to the above mentioned changes, such as the ring 50 forming part of a stop-motion such as 55 built under Letters Patent to Scott & Swinglehurst, No. 679,641, dated July 30, 1901, indicated at 66. This device operates upon the occurrence of a fault at the needle cylinder, and may have detector mechanism D mounted upon ring 3 having an adjustable feeler finger d such as that of Letters Patent to H. Swinglehurst 1,049,408 dated July 9, 1914, radially adjustable to contact with needles in carriers of different sizes.

60 At two or more points upon the ring 3 coming between seats 13 I may, for knitting ribbed fabric, erect posts 32 for the crossbar or arch 33 serving to support the sleeve 30, carrying for rotation the center spindle 34 65 carrying in turn support 29 for a needle dial

36, and a dial cam cap 35 fast to sleeve 30. It being necessary to hold the needle cylinder and needle dial with their verges nearly in contact, there may be provided for each size cylinder different size of dial 36. But I 70 save the duplication of parts of machines for different sizes of ribbed products by making the cams for coöperation with needles carried in grooves in said needle-dials changeable in diameter in a manner similar 75 to the variation in diameter of the cams for the cylinder needles. For this purpose I prefer to provide dial cam cap 35 with a series of radial slots 38 corresponding in number to the number of seats 12. Communicating with each of said slots on the under side of said dial cap 35 a number of radial seats 39 are provided in which bars 40 are seated for radial adjustment by means 80 of screws 41.

On the lower face of the bars 40 segmental cams 44 are fastened, as by screws 42. These cam segments may define between them any approved form of cam groove for coöperation with the butts of the dial needles held in 90 the dial 36, such as shown in Fig. 3, for instance.

Cam cap 35 and ring 3 rotate together in the form of the machine shown, but it will be understood that my invention is equally 95 applicable to types of machines in which the needle carriers are the driven elements, the cams being stationary. In order to prevent the needle dial 36 from rotating with the cap 35 I may make use of any approved device, preferably such as that shown (which is not a part of my invention), said device comprising an arm 55 fixed to the center 100 spindle and needle dial, bolts 56, a cam and gearing 60 in a housing 61, said gearing being driven from teeth 4 for working said bolts 56 alternately into and out of recesses in arm 55 to permit free passage of the yarn tubes 62, the supports 63 for a bobbin-stand 64, an operating connection 65 from an overhead break-detecting stop-motion, etc. The movements given the bolts 56 of this device have heretofore been varied to meet the needs of the number of yarn-feeds, etc., to be provided for, but by causing their operation for the passage, for instance, of each of the seats 12, a free passage will be opened for any number of yarn feeds placed as above referred to at each second, third, fourth, sixth, eighth or twelfth seat, and no change 115 need be made in the device for a variation in the number of yarns or connections corresponding to the varied number of feed points, the dial-holding device being provided of a standard form and operated at 120 the same frequency for machines variable to knit many different sizes of product. The radial position of the abutment formed by bolts 56, and the arm 55 may obviously be 125 the same for different sizes of needle car- 130

riers, and the dial cap 35, said arm 55, the bobbin stand 64 rotating therewith, yarn tubes 52, and said devices for holding the dial stationary may all therefore be of a single standard size for use with any diameter of cylinder and dial between wide limits.

The yarn feed guides 70 are preferably carried by the slides 40 as shown, and it will be understood that when the machine is adjusted for a change from one diameter to another diameter of needle carrier, no more will be required of the person making the change than to shift the needle cylinder and needle dial, and then to set all of the slides 15 11 and all of the slides 40 to their new positions.

Preferably, a change from one diameter of needle carrier to another will be accompanied by a change or shift of gearing G to cause the changed carrier to be driven at the standard peripheral speed, selected to give a maximum output with safety to the fabric and the machine parts.

While I have illustrated the cam carriers in connection with knitting needles, it will be understood that my invention is not restricted to cam carriers for operating needles only, but may be adapted without substantial change to coöperation with other movable knitting instruments, such as jacks, web-holders, loopers, or sinkers held for movement in carriers, cylinders or dials of different diameters, exchangeable to coöperate with operating cams therefor carried by cam carriers corresponding to this disclosure.

What I claim is:

1. A circular knitting machine having means for supporting carriers of one or another size for knitting instruments, cam-carriers and operating cams for said instruments, and means for supporting said operating cams on their carrier for adjustment to different positions to coöperate with one or with another of said carriers for the knitting instruments.

2. A circular knitting machine having means for supporting needle carriers of different sizes, and a needle cam carrier having means for supporting said needle cams in different positions for coöperation with each different needle carrier.

3. A circular knitting machine having cam carrier means variable to support operating cams in contact with the operating butts of needles held in circular carriers of different diameters.

4. A circular knitting machine having means for the concentric positioning of changeable needle carriers, cam carrier means, and adjustable devices carried by said cam carrier for supporting needle cams in operative contact with needle-carriers of different sizes, and means for rotating one of said carriers with respect to the other.

5. A circular knitting machine having a

bed-plate, concentric positioning means on said bed-plate for needle carriers of different sizes, a cam carrier ring, and a series of like movable needle cam supporting devices mounted for radial adjustment on said ring. 70

6. A knitting machine having a rotatable carrier element, and having on a permanent part of said machine a series of rigid seats for changeable instrument-carriers defining a series of positions accurately concentric 75 with the axis of rotation of said rotatable element.

7. A knitting machine changeable to knit fabrics of different sizes comprising means for concentrically positioning needle-carriers respectively of different sizes, a coöperating cam carrier, cams thereon, and means for adjusting said cams to coöperate with needle carriers of each respective size. 80

8. A knitting machine having a rotatable 85 cam-ring provided with seats, carrier bars radially adjustable in said seats, needle-cams on said carrier bars, and means adapted to support needle carriers of different diameters concentrically with respect to the axis 90 of rotation of said ring.

9. A circular knitting machine adapted for use with changeable needle-carriers of different size comprising a cam-carrier, a cam support on said carrier, and needle cams adjustable on said support substantially to define segments of surfaces of revolution of different diameters. 95

10. A knitting machine having cam devices, adapted to coöperate with circular instrument carriers of different size comprising a bar, a head on said bar, surfaces on said head, cam segments on said surfaces, means for adjusting said cam segments relatively to said head to define between them a 105 cam track occupying a segment of a cylinder of one or of another diameter, and means for adjusting said bar radially of said instrument carrier.

11. A rib knitting machine having in combination cylinder and dial needle operating means radially adjustable with respect to a central axis for coöperation with needle carriers of a plurality of different sizes. 110

12. A knitting machine having in combination a bed-plate, a rotatable carrier on said bed-plate, dial supporting means mounted on said carrier, and a dial cam cap mounted on said supporting means comprising needle-cams adjustable to coöperate with needle 120 dials of a plurality of different diameters.

13. A knitting machine having in combination a series of concentric seats for a needle cylinder, a concentric cam carrier ring, a concentric support for needle dials 125 of one or another diameter, a dial-cam cap; means on said carrier ring and said cam cap for supporting needle-operating cams in different adjustable concentric positions for coöperation with changeable cylinders and 130

- dials, and means for causing relative movement between a cylinder and said carrier ring and between a dial and said cam cap in unison for rib knitting.
- 5 14. A dial cam structure for knitting machines comprising a plate having seats extending outward from its center, adjustable bars, and means for fastening them in said seats, and needle cams carried by said bars.
- 10 15. A knitting machine having in combination a cam carrier ring, seats on said ring, a plurality of adjustable carriers for supporting cylinder needle cams on said ring, a needle dial, a similar plurality of 15 seats on said needle dial, means in said seats for supporting dial needle cams, and means for driving said ring and said dial cam cap in unison.
16. A knitting machine having in combination a cam carrier ring, seats on said ring, a plurality of adjustable carriers for supporting cylinder needle operating cams on said ring, a needle dial, a similar plurality of seats on said needle dial and means in 25 said seats for supporting dial needle oper-
- ating cams, and means for driving said ring and said dial cam cap in unison comprising gearing capable of being varied to maintain a constant rate of relative movement between needle carriers and needle-cams working at different diameters. 30
17. A circular rib knitting machine having in combination cylinder and dial needle operating means radially adjustable with respect to a central axis for coöperation with needle carriers of a plurality of different sizes, in combination with dial-holding means comprising a needle dial support, an element fixed with respect to said support, and holding means coöperating with said 35 element at a fixed radial distance from the center of said machine.

In testimony whereof, I have signed my name to this specification in the presence of two subscribing witnesses.

ROBERT W. SCOTT.
